PAPER ROLL HOLDER

Filed Nov. 16, 1938

FIG. 2

UNITED STATES PATENT OFFICE

2,255,861

PAPER ROLL HOLDER

Glenn A. Shaffer, De Pere, Wis., assignor to Fort Howard Paper Company, Green Bay, Wis., a corporation of Wisconsin

Application November 16, 1938, Serial No. 240,816

4 Claims. (Cl. 242—55.2)

The invention relates to paper-roll holders and has as an object the provision of a device designed to prevent pilfering of the roll while permitting its removal by a person familiar with the mechanism.

In public buildings considerable loss occurs to the management by reason of the stealing of the rolls of paper. This has been prevented by the provision of roll holders which are locked by means not accessible until the empty holder core may be destroyed to give access to the latch mechanism. This structure has the disadvantage that it is frequently desirable that a janitor when making his round be able to remove a nearly exhausted roll and replace the same with a fresh one without destruction of the remaining paper on the exhausted roll in order to avoid making more frequent rounds for paper supply.

Other structures have been proposed wherein the roll holder may be locked by means requiring a special implement for its release, which has the disadvantage that the implement must be carried and is likely to be not at hand when needed.

In accordance with the present invention anyone who knows the structure can readily release the roll but the means of release is exceedingly unlikely to be discovered by a would-be pilferer.

Further objects of the invention will appear from the following description when read in connection with the accompanying drawing showing an illustrative embodiment of the invention, and wherein:

Figure 1 is a plan view partly in central horizontal section of the holder with a roll in place; and

Figure 2 is a detail side elevation on a slightly reduced scale of the holder with the roll omitted.

As shown the device comprises a base 10 to be secured to a supporting structure. Fixedly mounted upon the base is an arm 11 which is opposed by the second arm 12 pivoted at 13 upon supporting ears 14 fixed upon the base 10.

To receive the hollow core of a roll of paper there are shown bosses 16, 15 carried by the arms 11 and 12. As is well understood, with the arm 12 swung to dotted line position in Figure 1 a roll of paper may be placed upon boss 16 and arm 12 may then be swung to position where its boss will enter the remaining end of the hollow core.

To latch the arms in closed position there is shown a projecting bar 17 shown as attached to the boss 16 by being passed through a slot in the boss together with an angle member 18

riveted thereto, the ends 19, 20 of the bar and angle being secured to the inner surface of the boss by any desired method.

The end of the bar 17 is shown as provided with a keeper opening 21 providing a keeper at its margin to engage a latch member 22 pivoted at 23 upon the inwardly projecting portion 24 of an angle member 25, the other portion thereof passing through the slot in the boss together with the latch 22 and being secured to the exterior surface of the boss. To urge the latch 22 toward the keeper, there is shown a tension spring 26 anchored at 27 and attached to the latch member 22 beyond its pivot.

The latch member 22 is shown as formed with an operating portion 28 projecting through the standard 12 to be engaged by a fingernail as shown in Figure 1. To prevent unauthorized operation of the latch by one unfamiliar with the mechanism, the keeper engaging portion of the latch is shown as provided with a tongue 29 projecting beyond a notch 30, which notch engages about the keeper forming margin of the keeper opening 21 whereby the tongue 29 hooks 25 with the keeper.

As is usual with holders of this type, leaf spring members 31, 32 are provided to preserve the centering of the roll in the holder, preventing endwise movement thereof. The said spring 32 in the present instance has a second function in addition to its usual function, that is, to hold the notch in the keeper opening 21.

The bar 17 is desirably made of spring metal and when so made the finger member 28 may be moved easily and as often as desired by a would-be pilferer without release of the latch or giving any indication of the mechanism.

If the arms 11 and 12 be relatively moved toward each other, as by the left hand as shown in Figure 1, the notch 30 will readily leave the keeper and the latch may be very easily operated even by a fingernail as indicated.

It will be seen that only relative movement of the arms 11 and 12 is required, for which purpose arm 11 might be given a slightly pivotal movement inward and none outward, and arm 12 may be pivoted for movement outwardly only.

By the expression "normal position of use" as applied to the arms and as used in the claims is meant the position they assume when the device is in use for the purpose intended, that is when a roll of paper is in place on the arms and ready to be unreeled for use. In the form of the invention shown in the drawing for purposes of illustration the position of the parts illustrated

in full lines is the normal position of use of all the parts.

Minor changes may be made in the physical embodiment of the invention within the scope of the appended claims without departing from the spirit thereof.

I claim:

1. A paper-roll holder comprising, in combination: a pair of arms mounted for relative movement toward and from each other; roll holding means carried by said arms; latch means to normally prevent movement of separation of said arms; spring means to hold said arms spaced to a limit preserved by said latch; and means to prevent release of said latch while the arms are so spaced operative because of such spacing.

2. The combination of claim 1 with means exposed externally of the roll and arms for manual operation of the latch toward releasing position.

3. A paper-roll holder comprising, in combination: a pair of arms; one of said arms mounted for movement toward and away from the other thereof; roll-holding bosses carried by said arms; a member having a keeper opening providing a keeper at an edge thereof, fixed to one of said arms to project toward the other arm within the core of a roll of paper, latch means mounted on the remaining arm for engagement with said

keeper; means to prevent separation of the latch and keeper operable by movement of the said one arm away from the other when the latch is engaged with the keeper and releasable by movement of the said one arm toward the other; and means accessible exteriorly of the roll to cause releasing movement of the latch.

4. A paper-roll holder comprising, in combination: a supporting base; an arm fixed on said base; a second arm pivoted to said base in spaced relation to the first named arm for movement toward and away from the same; means carried by said arms to support the respective ends of a roll core; a resilient bar carried by one of said arms to extend inside a roll core carried by said arms and formed with an opening providing a keeper at a margin thereof; a latch member pivotally mounted on the remaining arm to enter the core and having a recessed notch to embrace said keeper and providing a tongue to hook therewith to normally prevent separation of the latch and keeper; means carried by the latch, projecting through said movable arm for causing manual movement of the latch; and spring means urging said arms apart against the restraint of said latch.

GLENN A. SHAFFER.
